Inventor

UNITED STATES PATENT OFFICE.

LEO SIMMONS, OF WASHINGTON, DISTRICT OF COLUMBIA.

FLUSHING APPARATUS.

Application filed November 29, 1922. Serial No. 604,113.

To all whom it may concern:

Be it known that I, LEO SIMMONS, a citizen of the United States of America, and a resident of Washington, District of Columbia, have invented certain new and useful Improvements in and Relating to Flushing Apparatus, of which the following is a specification.

This invention relates to certain improvements in flushing apparatus; and the objects and nature of the invention will be readily understood by those skilled in the art in the light of the following explanations of the accompanying drawings that illustrate what I now believe to be the preferred mechanical expressions or embodiments of my invention from among other constructions, and arrangements within the spirit and scope thereof.

20 Referring to the accompanying drawings forming part hereof:

Fig. 1 shows flushing apparatus embodying various features of my invention in vertical section, certain parts being shown partially in elevation.

Fig. 2 is a detail section on the line 2—2, Fig. 1.

Figs. 3, 4 and 5 are detail views.

In the drawings, I show a water supply pipe 1 supplying water under head or pressure to the flushing apparatus, and flushing water connection 2 leading to the toilet or other device to be flushed, from the flushing apparatus.

35 The apparatus embodies a shell or casing that provides an upper pressure or water supply chamber *a*, a lower flushing water discharge chamber *b* and a vertical passage or discharge port *c* from the bottom of chamber *a* to top or chamber *b*, and controlled and normally closed by a lift valve mechanism.

In the particular example illustrated, the shell or casing comprises a lower hollow section 3 and an upper hollow section 4. The upper section 4 is, in this example, approximately in the form of a T union or coupling that is longitudinally threaded both internally and externally at its open upper end, and contracted at its lower end to provide washer seat 4^a, the discharge passage *c*, depending threaded nipple 4^b, and annular exterior downwardly facing shoulder 4^c. In this example, said section 4, is also formed 55 with a lateral supply water inlet between its upper and lower ends, that extends

through radial exterior neck 4^d internally threaded to receive the water supply pipe 1. This neck 4^d is preferably angularly formed 60 exteriorly to receive a wrench.

The casing section 3, in this example is formed with a tapped vertical top opening that receives the nipple 4^b so that the two sections are coupled together by a screw threaded connection. By this sectional casing arrangement, the upper section 4 can be rotated on a vertical axis with respect to section 3 to cause the neck 4^d to project in any desired direction from such vertical axis to accommodate various installation 70 conditions (see dotted lines Fig. 1) particularly with respect to relative positions of water supply and discharge connections, although I do not wish to so limit all features 75 of my invention.

In the example illustrated, the otherwise open top end of the shell of section 4, is closed by a flanged internally threaded cap 5 that covers and exteriorly fits the upper end of the section and is removably coupled thereto by the screw threaded connection between the exterior of the section and interior of the cap flange. This cap 5 usually carries a packing washer that fits the top 80 edge of section 4 to provide a water tight joint. This cap 5 is exteriorly formed with an upwardly projecting boss 5^a providing an exterior wrench-receiving portion that terminates in a central vertical threaded post or stem 5^b. The cap 5 and its boss 5^a 85 are not usually exteriorly finished and plated but are left in the rough so as not to be easily damaged by the application thereto of wrenches and other tools in the hands of mechanics. This cap is applied and removed to gain access to the interior of the casing for the adjustment and replacement of parts, and mechanics usually mar and damage polished and plated surfaces by the application of tools thereto. I hence preferably leave the exterior surface of the cap 90 unfinished, and cover the same by suitable exposed ornamental finishing means that can be easily removed without the use of tools to permit access to the cap which requires a tool for removal and application.

I show for this purpose, an ornamental exteriorly-finished, thin metal cover cap 6 formed to drop down over and cover the cap 5 and exteriorly fit down around the cap 105 flange. This cap has a central vertical top opening through which the threaded post 5^b

projects upwardly. In this instance, the ornamental cover cap 6 is removably held in place on cap 5 by round metal head or disk 7 having a central threaded socket receiving the upper end of post 5^b and removably screwing thereonto to lock and release the cover cap. This disk 7 is preferably formed at its peripheral edge with an annular groove receiving rubber or other cushioning ring 8 to be contacted by the closet seat cover. In other words, the disk 7 and its ring 8 constitute a bumper for the seat cover while the disk also serves as means for normally holding or locking the removable ornamental cover cap over the unfinished cap 5. The bumper presents an annular cushioning body, hence a cushioning stop for the seat cover is provided whatever the adjustment of the nut-forming disk 7 or of the casing section 4 with respect to section 3. When it is necessary for the mechanic to gain access to the interior of the casing, he can unscrew the nut-forming bumper disk 7 and remove the ornamental or finishing cover 6 without the use of surface marring tools. The cap 5 having the unfinished surface is thus uncovered so that the mechanic can apply his wrench thereto.

The main flushing valve 9, and the pressure relief or auxiliary valve 10 are arranged and vertically movable within the upper or water supply chamber *a* of the casing, and are controlled in their vertical movements by a vertical lift rod 11 having longitudinal upward continuation 11^a loosely fitting and vertically movable in the vertical guide socket 5^a in the cap 5. The seat for valve 9 is formed by an annular washer 12 of leather or other suitable durable cushioning material, seated on the ledge or seat 4^a at lower end of casing section 4 and snugly fitted within said section. This washer 12 is removably held clamped down on its seat by a vertically-slidable washer retaining device or spider consisting of a vertically movable ring 13, fitting down on the top surface of the washer and within the inner surface of the casing section and having spaced vertical wings 13^a fitting the inner surface of the casing section, and engaged at their top edges by a ring nut 14 screwed into the upper end of the casing section. The spider 13-13^a, can be held against rotation within the casing section, by a rib 13^b, slidable vertically in a vertical groove 5^c in the casing wall. The ring nut is notched to receive a tool for rotating the same to remove the nut and for rotating the same to force down the spider to clamp the washer. The nut and spider can be removed from the casing section to permit removal and replacement of the washer. This arrangement permits adjustment of the washer from the upper end of the casing through rotation of ring nut 14, which is

readily accessible when cap 5 is removed. Also, the washer and its securing means are thereby rendered easy of assembly within the casing.

In the example shown, the main valve 9 is in the form of a truncated cone formed of a block of metal or other suitable material, formed with a central vertical bore or pressure relief passage 9^a through which the lift rod 11 extends and in which it is vertically movable. The upper end of the cone valve 9 is formed with a depressed seat or central top socket in which annular washer 9^b is seated. This washer 9^b forms the seat for the conical relief or auxiliary valve 10, and is held down on its seat by a spider or cap 9^c removably screwed into the upper end of valve 9 and limiting the independent vertical movement of valve 10. The cap 9^c can be adjusted vertically with respect to valve 9 to vary the limit of independent movement of the auxiliary valve as the upper end of the cap or spider 9^c overhangs the upper end of valve 10 to form a stop limiting the relative vertical movement of valve 10, and whereby the valve 9 is lifted by valve 10. The spider or cap 9^c is constantly open to free passage of water from chamber *a* into the interior of the spider for flow through relief passage 9^a when that passage is open. The spider is preferably interiorly large with respect to valve 10, so that valve 9 is more or less loosely hung on and free to swing laterally with respect to valve 10 in properly seating.

Various means can be provided for manually operating the lift rod 11 to elevate the relief valve 10 to start the flow of water through the main valve 9, and then to elevate the main valve by the engagement of valve 10 with the top or spider 9^c to start the full flushing flow. For instance, in this example, I show, a rotary or oscillatory stem 16 extending transversely through the casing and having exterior lateral or radial operating handle 17, and within the casing having lateral lifting arm or finger 18 at its free end in operative lifting engagement with that portion of the lifting rod within the chamber *b* formed by casing section 3.

In the example illustrated, the lower portion 3 of the casing is extended laterally to provide an offset outlet for the flushing water chamber *b*, and this outlet from a depending discharge neck or mouth 3^a formed to be coupled to the flushing water offtake 2. The lower portion 3 of the casing is formed with an interiorly screw threaded opening aligned with the longitudinal axes of the lift rod 11 and of the valves 9, 10, and this opening receives the upper end of a depending cylindrical dash pot cup or cylinder 19, screw threaded at its upper end to screw into said opening and thus form a downwardly continuation of the casing.

This cup is open at its upper end into chamber *b* and closed at its bottom and side walls.

The lower end of the lift rod 11 is provided with a dash pot piston 20, that works vertically in said cup to control the closing movements of the valves 9, 10, and hence predetermine the approximate volume or quantity of water discharged at each flushing operation. The piston is formed to rise 10 freely with the lifting rod when that rod is elevated by manipulation of handle 17, and to slowly descend under the pressure of the water and the weight of the parts then carried by the piston.

15 The piston head 20 loosely fits in the cup, but is equipped with a flexible cup washer 21 having its flexible annular depending skirt formed to expand and prevent upward flow of water within the cup past the piston, 20 as usual. However, the lower end of the piston head within the skirt of the washer, is contracted or reduced in diameter to permit such inward contraction of the lower end of the skirt, when the piston is located 25 at the upper end of the cup, as to cause downward flow of water past the piston into the cup, and to facilitate this operation of quickly filling the cup with water when the valves are raised and before they start on 30 their closing strokes, I show the upper end of the cup interior slightly enlarged by an outward flare or bevel 19^a, see in particular Fig. 3, showing the piston approximately at its limit of upward movement.

35 The object, is to assure the complete filling of the cup with water, before the piston starts on its downward movement and the valves start on their closing movements. The instant the piston starts down, the cup 40 washer 21 expands against the inner surface of the cup against upward passage of water from the cup past the piston, thereby exerting more or less pressure on the water in the cup. Hence an outlet for the water 45 from the cup must be provided and the speed of the descend of the piston can be controlled by controlling the flow of water from the cup. For instance, I provide a water discharge and inlet channel or duct

50 23 arranged longitudinally of and within the wall of the cup, leading from the interior of the lower end of the cup and at its upper end 23^b, opening through the top edge of the cup into the flushing water chamber 55 *b* of the casing. The lower end of this duct 23 opens into the lower end of the cup through the medium of radial port 23^a, and an adjustable tapered end set screw or pointed valve screw 24 is provided for varying 60 the discharge capacity of this port 23^a.

The set screw 24 is longitudinally adjustable in a tapped hole formed radially through the wall of the cup opposite and aligned with the radial port 23^a. The head 65 of the set screw 24 is accessible at the ex-

terior of the casing and cup and is formed to receive a screw driver or other implement by which the set screw can be rotated to increase or diminish the capacity of discharge port 23^a and the flow of water therethrough. 70

By this means, the rate of flow of water from the cup can be easily and accurately adjusted to suit various conditions and to control the quantity of water discharged at each flushing operation. Under like conditions, the quantity of water discharged at a flushing operation, is determined by the length of time it takes the valves to close from completely opened positions. However, water pressure and other conditions 75 vary at different locations, and even from time to time in the same installation. These various conditions can be taken care of by the single simple adjustment screw 24, from the exterior of the casing, without the necessity of gaining access to interior parts. 80

It is obvious that when the piston 20 is drawn upwardly by the valve opening movement, water will be drawn into the cup through the duct 23 and port 23^a, possibly 85 sufficient water to fill the cup, and if this occurs, the beveled end 19^a and contractile washer skirt 21, are unnecessary, but these last named features assure the quick filling of the cup on the completion of the upward 90 stroke of the piston, under all conditions.

If so desired, the duct 23 can be formed by a longitudinal groove cast or otherwise formed in the inner surface of the casting forming the cup, and the duct and port formation and the beveled upper end formation of the cup, can be completed by the insertion of a cup lining tube 25 to cover the groove and form the duct and to provide the port 23^a. 100

105 Material advantages are gained by the reversal of flow of water under pressure from time to time through channel 23 and port 23^a, as the channel and port are thereby rendered self cleaning. If foreign matter tends to clog the port or channel, the forced water flow in opposite directions removes the obstruction. 110

In the example shown, the stem or spindle 11 extends transversely through the casing 115 to one side of the lift rod 11, and the side walls of the casing are formed with opposite aligned hollow bosses 16^a, forming bearings for said stem 16. One of these bosses is closed against water leakage by a cap 27 containing a packing washer compressed against the outer edge of the bearing boss, as the stem 16 terminates within the last named bearing boss. However, the stem extends to the exterior of the opposite bearing boss to receive the handle 17. This bearing boss is exteriorly threaded to receive a threaded cap, or packing nut or gland 28, containing suitable packing 29 compressed around the stem and against the edge of the 120 125 130

boss. Great difficulty has been experienced in preventing leakage along the stem and through the packing nut 28, while avoiding so much friction on the stem as to resist free rotation or movement thereof. If the gland was tightened sufficiently to prevent water leakage, the stem was gripped too tightly by the packing and the stem was not free to rotate.

I have most effectively overcome this difficulty by forming an annular small smooth-faced groove 30 around the portion of the stem or handle shaft 16 that is surrounded by the packing. This groove is located within the packing nut at the exterior of the bearing boss, and I find that the packing expands into the groove and tightly seals the outer end of the boss against leakage yet leaves the stem free to rotate or oscillate without excessive friction or restraint.

It is evident that various changes, modifications, and departures might be resorted to without departing from the spirit and scope of my invention, and hence I do not wish to limit myself to the exact disclosure hereof.

What I claim is:—

1. Flushing apparatus comprising a casing embodying an upper pressure chamber, a lower flushing water chamber having a lateral flushing water outlet, a flushing water port from the pressure chamber to said lower chamber; flushing valve mechanism controlling said port and embodying a main lift valve in the pressure chamber having a pressure relief passage, a relief valve for closing and opening said relief passage, said valves being closed solely by gravity and water pressure, a lift stem operatively connected with said valves to control the closing movements thereof, and provided with operating means for lifting said valves in succession against gravity and water pressure; the lower end of said stem provided with a piston having an annular depending contractile cup washer; a dash pot cup alined with said stem and receiving said piston and arranged at the lower end of the flushing water chamber, the upper end of said cup being open into said chamber below said lateral outlet, the upper end of said cup being formed to permit quick filling of the cup when the piston is approximately at its limit of upward movement, said cup having a radial port at its lower end and a duct leading therefrom to the upper edge of said cup and open adjacent to said flushing water outlet, and a normally stationary valve screw for controlling the capacity of said radial port, said screw adjustable from the exterior of the casing, said piston and cup constructed and arranged to control the closing movement of said valves solely by the outflow through said radial port, the walls of the cup below its upper end being otherwise imperforate.

2. Flushing apparatus comprising main and relief flushing valves, a casing providing a flushing water passage, a lift stem for said valves, a piston carried by said stem for controlling the closing movement of the valves, a dash pot cup receiving said piston and carried by said casing and at its upper end open to said passage, said cup provided with a longitudinal water duct open to said passage at its upper end at the top edge of said cup and at its lower end having a port opening into the lower end of the cup, a normally fixed member adjustable from the exterior of the casing for controlling the capacity of said port, said piston and the cup being relatively formed to permit flow of water past the piston during ascent of the piston and to prevent water leakage except through said port and duct during descent of the piston, said piston and the upper end portion of the cup being relatively formed to permit quick inflow of water under the piston when approximately at its limit of upward movement.

3. Flushing apparatus comprising a casing providing a pressure water chamber having a bottom port, a flushing water chamber below said port, and a dash pot cup alined with said port and at its upper end open to said flushing water chamber and otherwise closed except for a radial perforation at the lower end of the cup, a lift stem arranged in said chambers and extending through said port and provided with a piston fitted in said cup, main and relief flushing valves carried and controlled by said stem and controlling said port, the wall of said cup formed with a longitudinal groove opening through the top edge of the cup and extending to the lower end portion thereof, said provided with an inner surface-forming lining sleeve covering said groove to form a duct and at the lower end portion of said duct formed with said perforation opening into the duct formed with said perforation opening into the duct, and a normally fixed screw adjustable from the exterior of the cup and controlling the capacity of said perforation.

4. In flushing apparatus, a casing having a flushing water passage with an annular valve seat formed by an annular compressible washer, a conical main lift valve normally fitting down within the center opening of said washer and seated thereon closing said passage, said main valve having a longitudinal pressure relief passage with a depressed top annular valve seat formed by an annular washer, and a lift rod extending loosely through said relief passage and carrying an auxiliary conical valve normally seated in said relief passage valve seat, said main valve provided with an upstanding stop and washer-securing spider member extending to a point above and limiting the

independent vertical movement of said auxiliary valve and by which the auxiliary valve lifts the main valve, said member being constantly open for flow of water therethrough and normally out of contact with the auxiliary valve.

5. Flushing apparatus comprising a casing providing a top pressure water chamber, a bottom flushing water passage, and a bottom vertical flushing water port from the pressure chamber surrounded by an annular washer supporting ledge, an annular compressible washer fitting the bottom of the pressure chamber and seated on said ledge and overhanging said port, a valve lift stem in said chambers and extending through said port, main flushing and pressure relief lift valves controlling said port and controlled in their vertical movements by said stem, means for lifting said stem to open said valves, means controlling the descent of said stem and the closing movement of said valves, the main flushing valve being of conical formation and normally fitting down within said washer, said casing having a removable top closure for said pressure chamber, the upper portion of the casing being internally screw threaded, a vertically slidable removable ring in the casing for compressing said washer against said ledge and provided with spaced upright arms, and a removable ring nut fitting said screw threads and engaging the upper ends of said arms.
35. 6. Flushing apparatus comprising a casing providing a pressure water chamber with an outlet port and a flushing water passage, gravity and water pressure seated lift valves controlling said port and embodying a main flushing valve and a relief valve, a stem for lifting said valves and con-

trolling the gravity and water pressure closing movement thereof, means controlling the descent of said stem, a freely turnable rock shaft mounted in the casing and operatively connected to said stem to lift the same and said valves and provided with an exterior operating handle, said casing providing a bearing for said shaft having a projecting exteriorly threaded nipple, said shaft having an annular smooth-surface groove at the outer end portion of said nipple, a threaded cap surrounding said shaft beyond and screwing on said nipple, and packing within the cap and surrounding the shaft and expanded into said groove to seal the same against outward leakage along the shaft without binding the shaft against free rotation under the weight of the valves and stem.

7. Flushing apparatus comprising a casing providing a top water pressure chamber and a flushing water passage, flushing valve means in said chamber and controlling the flow of water therefrom, operating and controlling means therefor, a top end removable closure for said casing whereby access can be gained to said chamber and the valve means therein, said closure having an exterior wrench face and a central threaded upwardly projecting stem, a removable thin ornamental exterior slip cover normally covering said closure and having a central top opening receiving said stem, and a removable finger disk forming a clamping nut normally screwed onto said stem to secure said cover, said disk formed with an annular cushioning rim to form a closet seat bumper.

Signed at Washington, D. C., this 27th day of November, 1922.

LEO SIMMONS.
